UNITED STATES PATENT OFFICE.

JOHN J. LANGDON, OF PUEBLO, COLORADO.

BOOKCASE.

1,269,825.

Specification of Letters Patent. Patented June 18, 1918.

Application filed June 27, 1917. Serial No. 177,388.

To all whom it may concern:

Be it known that I, JOHN J. LANGDON, a citizen of the United States, residing at Pueblo, in the county of Pueblo and State of Colorado, have invented certain new and useful Improvements in Bookcases, of which the following is a specification, reference being had to the accompanying drawings.

This invention relates to certain improvements in bookcases and has relation more particularly to a device of this general character of a revolving type and it is an object of the invention to provide a device of this general character including a plurality of shelves adapted to rotate about a common center together with means co-acting with said shelves for maintaining the same substantially horizontal at all times.

It is also an object of the invention to provide a device of this general character having novel and improved means whereby the shelves are normally maintained against movement.

It is also an object of the invention to provide a novel and improved device of this general character including a table together with a rotating carrier having operatively engaged therewith a plurality of shelves, said carrier being so arranged as to position an uppermost shelf substantially flush with the table.

The invention consists in the details of construction and in the combination and arrangement of the several parts of my improved bookcase wherein certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood I will now proceed to describe the same with reference to the accompanying drawings wherein:

Figure 1 is a view in side elevation illustrating a case constructed in accordance with an embodiment of my invention;

Fig. 2 is a view in end elevation of my improved case as herein embodied with the table or desk portion omitted;

Fig. 3 is an enlarged fragmentary view partly in elevation and partly in section illustrating a support as herein embodied

with a book operatively mounted thereon, and

Fig. 4 is an enlarged fragmentary view partly in elevation and partly in section illustrating a book carried by one of the supports and in open position.

As disclosed in the accompanying drawings T denotes a table or desk top supported in a desired manner and having its central portion cut away as clearly indicated in Fig. 65 1 of the accompanying drawings. Pivotally engaged with one of the inner margins of the table T is a hinged leaf 1 having a tail portion 2 underlying the co-acting marginal portion of the top or table whereby it will be 70 perceived that the leaf 1 is normally maintained in a horizontal position yet is capable of free upward swinging movement.

At substantially the center of the open portion of the table or top T and arranged 75 therebelow are the upstanding transversely spaced standards 3 which support the fixed shaft 4, one end portion of said shaft 4 being offset upwardly as indicated at 5. Loosely mounted upon the lower portion of 80 the shaft 4 is a hub 6 having secured at its opposite end portions the wheels 7 of equal diameter and which have their peripheral portions connected by the supporting shafts 8, loosely supported by said wheels 7. 85 Loosely mounted upon the offset portion 5 of the shaft 4 is a third wheel 9 of the same diameter as the wheel 7 and loosely mounted with the peripheral portion of said wheel 9 are the cranks 10 carried by the adjacent 90 ends of the shafts 8. The cranks 10 are perpendicularly related to the shafts 8 and are of the same length as the distance between the shaft 4 to the offset portion 5 thereof.

Fixed to each of the shafts 8 is a shelf 11 95 and to facilitate the operative engagement of the shelf 11 with the shaft the portion thereof intermediate the wheels 7 is flattened as indicated at 12 in detail Figs. 3 and 4. Pivotally engaged with a marginal portion 100 of each of the shelves 11 are the spaced spring clips 14. The clips 14 are adapted to have clamping action upon the back portion of a book B. It is thought to be clearly obvious from the foregoing description and 105 from the illustration in the accompanying drawings that as the wheels 7 and 9 are rotated the shelf 11 will at all times remain horizontal. The wheels may be rotated in any manner but preferably by manually op- 110

erating the upper portion of the wheel 9 which extends above the table or top T. The upper portions of the wheels 7 are so positioned as to bring the uppermost shelf 11 substantially flush with the table or top T and when the uppermost book is thrown into an open position as indicated in Fig. 4 a part of the book is supported by the leaf 1. It will also be self evident that the upward 10 swinging movement of the leaf 1 prevents said leaf from offering any obstruction to the rotation of the wheels 7 and 9 by contact of the books B therewith.

I prefer that the hinged end portion of 15 each of the clips 14 be provided with an extension or tail 15 adapted to engage the under surface of the co-acting shelf 11. The tail 15 is of such an angle as to prevent the clip 14 from dropping below the horizontal. 20 My improved bookcase is especially adapted for use in county or abstract offices or in offices where many indexes are used. The books B upon the shelves 11 constitute record books and as herein embodied said books will be numbered from 1 to 10 with 25 said numbers preferably positioned upon the index plates 16 carried by the cranks 10. Each of the plates 16 has arranged thereon an index for the book supported by the adjacent shelf 11. If the operator is desirous 30 of making a record commencing with the letter "A" he revolves the wheel 9 until book number 1 is flush with the table or top T. The index plate on the crank 10 will readily 35 advise him as to the page of the book to which he should turn and so on.

The wheels 7 and 9 are normally held 40 against rotation by the brake shoes 17 engageable with the peripheries of the wheels 7 and carried by the end portions of the arms 18 fixed intermediate their lengths to the shaft 19 suitably supported for rocking movement. The opposite end portions of 45 each of the arms 18 have coacting therewith the retractile members 20' which serve to maintain the shoes 17 constantly in contact with the wheels 7. One of the arms 18 adjacent the shoes 17 is provided with the 50 standing pedal 20 whereby the shoes 17 may be readily forced out of frictional engagement with the wheel 7 when it is desired to rotate the same.

From the foregoing description, it is

thought to be obvious that a bookcase constructed in accordance with my invention is 55 particularly well adapted for use by reason of the convenience and facility with which it may be assembled and operated and it will also be obvious that my invention is susceptible of some change and modification without materially departing from the appearance and spirit thereof and for this reason I do not wish to be understood as limiting myself to the precise arrangement and formation of the several parts herein shown in 60 carrying out my invention in practice except as hereinafter claimed.

I claim:

1. A device of the character described comprising a rotary member, a shaft loosely supported by said member, a shelf engaged with the shaft, a second rotary member positioned eccentrically with relation to the first named rotary member, said shaft being provided with a crank operatively engaged 70 with the second rotary member whereby the shelf is maintained substantially horizontal upon rotation of the members, and an upwardly swinging leaf interposed in the line of travel of the shelf, said shelf being substantially flush with the leaf when the shelf is at the limit of its upward movement.

2. A device of the character described comprising a rotary member, a shaft loosely supported by said member, a shelf engaged 85 with the shaft, a second rotary member positioned eccentrically with relation to the first named rotary member, said shaft being provided with a crank operatively engaged with the second rotary member whereby the 90 shelf is maintained substantially horizontal upon rotation of the members, an upwardly swinging leaf interposed in the line of travel of the shelf, said shelf being substantially flush with the leaf when the shelf is at 95 the limit of its upward movement, and means co-acting with the leaf for preventing the same dropping below substantially the horizontal.

In testimony whereof I hereunto affix my 100 signature in the presence of two witnesses.

JOHN J. LANGDON.

Witnesses:

J. A. LANGDON,
J. RAY LANGDON.
